CLAIM

I claim the ornamental design for an aperture insert component, as shown and described.

DESCRIPTION

FIG. 1 is a top perspective view of an aperture insert component showing my new design;

FIG. 2 is a bottom perspective view of the claimed design of FIG. 1;

FIG. 3 is a top view of the claimed design of FIG. 1;

FIG. 4 is a bottom view of the claimed design of FIG. 1;

FIG. 5 is a front view of the claimed design of FIG. 1;

FIG. 6 is a left side view of the claimed design of FIG. 1; and,

FIG. 7 is a right side view of the claimed design of FIG. 1. The dashed broken lines shown in the drawings depict portions of the aperture insert component that form no part of the claimed design.
